DRUM PRACTICE DEVICE

Sam H. Smirin, Denver, Colo.

Application March 2, 1954, Serial No. 29,288

Term of patent 3½ years

(Cl. D56—1)

FIG. 2

FIG. 3

FIG. 1

To all whom it may concern:

Be it known that I, Sam H. Smirin, a citizen of the United States and a resident of the city and county of Denver, State of Colorado, have invented a new, original, and ornamental Design for a Drum Practice Device, of which the following is a specification, reference being had to the accompanying drawing, forming a part hereof.

Figure 1 is a plan view of a drum practice device showing my new design.

Figure 2 is a perspective view thereof; and

Figure 3 is a section taken on line 3—3 of FIG. 1 but on a greatly reduced scale.

I claim:

The ornamental design for a drum practice device, as shown.
